Letters Patent No. 891, Dated May 26th 1857.

.....
The schedule referred to in these Letters Patent, and making part of the same.

.....
To all whom it may concern: Be it known that we, Garrison Smith,

Henry Brown & Samuel H. Taylor, of the City and County of Philadelphia, and State of Pennsylvania, have invented or produced a new and original Stove design, called the "Noble Cook"; and we do hereby declare that the following is a full, clear, and exact description of the said design, reference being had to the annexed drawings, forming part of this invention, in which

Figure 1, is a side elevation of the stove.

Figure 2, is a front elevation; and

Figure 3, is a rear elevation.

Similar characters of reference in the several figures denote the same part.

The side plate A, bears the three panels B, C, and D, raised by mouldings E, F, G. The panel B, is embellished by sweeping foliage a, b, c and projections d, constituting an ornament in bas-relief, the details of which are fully shown in figure 1.

Panel C, is ornamented by the entwined foliage e, f, in bas-relief; and panel D, bears an ornament made up of foliage; the design, configuration and arrangement of the ornaments of said panels being as fully shown in figure 1.

On the side plate below the panels is the scroll tablet H, and at the ends of the plate are the wavy ornaments I, and J, J'. Above the panels is the inscription, "Noble Cook", in raised capitals.

The front doors P, P', are raised by mouldings R, R', and bear ornaments in bas-relief, made up of foliage g, h, arranged and configured as shown in figure 2. The upper front plate Q, has a waving ornament of foliage h, h', at each end thereof; and the lower front plate T, has an embellishment along its side and bottom edges made up of figures i, j, k; the arrangement and configuration of these several ornaments being fully shown in figure 2.

The lower front plate has a panel with the inscription "Patented 1857"; and below the panel is the inscription
